Williamson, Peirce & Williamson

UNITED STATES PATENT OFFICE.

EARL ECK, OF MINNEAPOLIS, MINNESOTA.

FISH-POLE HOLDER AND OARLOCK.

Application filed February 19, 1927. Serial No. 169,561.

This invention relates to fishing equipment or apparatus, and especially to devices for holding fishing poles or casting rods from a row boat.

5 It is ordinarily a very difficult task for an oarsman to fish as he propels a row boat or holds the same against the wind, since most of his attention is devoted to the oars and the enjoyment as well as the success of the sport 10 is thereby greatly diminished.

It is an object of my invention to provide an extremely simple but highly efficient device adapted to be readily applied to an ordinary row boat and adapted to hold a 15 pole or casting rod laterally from the boat and to moreover impart an irregular movement to the line as the boat is moved.

Another object of my invention is to provide a highly efficient combination oar lock 20 and fish pole holder adapted to engage and retain the handle portion of a casting rod or fish pole to support the same in proper position for fishing, said device being so constructed that a pole or rod may be instantly 25 attached or detached.

A still further object is to provide in a device of the class above described, means for readily adjusting the holder in various tilted positions and means for yieldingly 30 securing the rod or pole in a socket.

These and other objects of the invention will be apparent from the following description made in connection with the accompanying drawings wherein like reference characters refer to similar parts throughout the 35 several views, and in which:

Fig. 1 is a perspective view showing a preferred embodiment of my device applied to the gunwale of a row boat, a portion of a 40 bamboo fish pole shown in dotted lines;

Fig. 2 is a vertical section taken through the center line of the pole holder;

Fig. 3 is an end elevation of the pole holder or socket detached; and

45 Fig. 4 is an enlarged longitudinal section of the pole socket taken on the line 4—4 of Fig. 3.

In the drawings, a portion of the gunwale of an ordinary row boat is indicated by the 50 numeral 5, having mounted thereon a relatively heavy oar lock block 6. Block 6 is provided with the usual bearing socket 7 to receive the pintle 8 of the oar lock. My oar lock resembles, in a general way, the usual 55 type of oar lock employed but has one arm 9 of its crotch or forked portion extended

considerably above the opposite arm. A portion of an oar X is shown in operative position in the oar lock. The extended portion of the arm 9 is provided with a flat 60 substantially vertical surface 9^a preferably slightly skewed in reference to arm 9, and a segmental shaped bracket 10 is pivoted thereto on a horizontal axis. Bracket 10 has a depending flat flange, which may be pivoted 65 to the extended portion of arm 9 by means of a rivet or pin 11, and said flange is also provided with an arcuate slot 10^a concentric with pivot 11. A laterally extending threaded bolt 12 is rigidly carried by the arm 9 70 and is passed through slot 10^a having its outer end engaged by a winged clamping nut 13. Bracket 10 includes an arcuate supporting plate 10^b rigidly secured to its upper edge to which is secured a tubular carrier or 75 socket 14, said socket being of slightly larger cross section than an ordinary fish pole or casting rod. An inturned annular flange 14^a is provided at the lower end of socket 14 against which the pole or rod is adapted to 80 abut, while the upper end of the socket is open and provided with a plurality of resilient fingers 15. Fingers 15 may be of any desirable construction, but as shown, comprise spring clips rigidly secured to the outer 85 surface of socket 14 and each having an inwardly curved engaging portion 15^a working through a longitudinal slot in the upper portion of socket 14. The engaging portions 15^a of said fingers are circumferentially 90 spaced within the interior of said socket and obviously will engage the handle portion of a pole or rod to yieldingly retain the same. A recess 16 is formed in the upper portion of socket 14 to permit the rod or pole to be 95 more easily withdrawn.

The operation and utility of my device is probably obvious from the foregoing description, but may be briefly summarized as follows:

A person may cast or fling out his line, fitting the butt of the pole or rod in socket 14 and may then manipulate the oars as desired, the movement of the oars also putting an irregular jerking movement on the line. This 105 movement of the line causes the bait to move irregularly and to attract the fish. The oarsman will readily detect a bite and can then quickly grasp the handle of the rod or pole and manipulate the same to land the 110 fish. It will be noticed, that in all positions of the oar the holder as well as the rod or

5 pole will be radially extended from the socket of the oar lock. The flange 14^a will prevent a small rod or pole from slipping through the socket, while the fingers 15 will supply sufficient friction to prevent the pole 10 from falling out or from being pulled out when the bait is struck. It is often desirable in my device to adjust the tilted position of socket 14, and this may be accomplished by 15 manipulating the winged nut 13 and again setting the same with the socket in the desired position.

From the foregoing description, it will be seen that I have invented a highly efficient 15 combination oar lock and fish hole holder, capable of being readily utilized on any standard form of row boat, and making it possible for a person to fish and row the boat at the same time. Extensive actual usage 20 of the device has proven the same to be successful for the purposes intended.

It will, of course, be understood that various changes may be made in the form, details, arrangement and proportions of the 25 parts without departing from the scope of the invention.

What is claimed is:

1. A combined oar lock and fish pole holder comprising a pintle adapted to be seated in an oar lock socket, a crotch carried by said pintle adapted to receive an oar and a socket carried by an arm of said crotch adapted to detachably hold the handle of a fish pole or casting rod therein.
2. A combined oar lock and fish pole holder comprising an oar lock portion adapted to be mounted in the gunwale of a boat, said portion including an upwardly extended arm, a tubular socket carried by 40 said arm and adjustable in a plurality of

tilted positions relatively thereto, said socket having an open end adapted to receive the handle of a fish pole or casting rod, and having a restricted end adapted to abut the object held therein.

45

3. A combined oar lock and fish pole holder comprising an oar lock portion adapted to be pivotally mounted on the gunwale of a boat, said portion having a vertically projected arm, a bracket mounted 50 on said arm and swingable thereon a horizontal pivot, means for clamping said bracket rigidly to said arm in a desired position, and a socket carried by said bracket adapted to hold the handle of a fish pole or 55 casting rod.

4. The structure set forth in claim 3, and means for yieldingly holding a pole or casting rod in said socket.

5. A combined oar lock and fish pole 60 holder comprising an oar lock portion adapted to be pivotally mounted on the gunwale of a boat and means connected with said oar lock portion and carried thereby for holding the handle portion of a fish pole 65 with said pole projecting laterally from a boat.

6. A combined oar lock and fish pole holder comprising an oar lock member adapted to be pivotally mounted on the gunwale of a boat, a bracket pivoted to said oar lock member on substantially a horizontal axis, means rigidly carried by said bracket and engaging and retaining the butt of a fish pole and means for securing said bracket 70 to said oar lock member in a desired radial position thereto.
